CLAIM

The ornamental design for a bed sheet, as shown and described.

DESCRIPTION

FIG. 1 is a top perspective view of a first embodiment of a bed sheet;

FIG. 2 is a bottom perspective view thereof;

FIG. 3 is a left-side view thereof;

FIG. 4 is a right-side view thereof;

FIG. 5 is a front view thereof;

FIG. 6 is a back view thereof;

FIG. 7 is a top view thereof;

FIG. 8 is a bottom view thereof;

FIG. 9 is a second perspective view thereof showing the bed sheet in an alternate position;

FIG. 10 is a top perspective view of a second embodiment of a bed sheet;

FIG. 11 is a bottom perspective view thereof;

FIG. 12 is a left-side view thereof;

FIG. 13 is a right-side view thereof;

FIG. 14 is a front view thereof;

FIG. 15 is a back view thereof;

FIG. 16 is a top view thereof;

FIG. 17 is a bottom view thereof; and,

FIG. 18 is a second perspective view thereof showing the bed sheet in an alternate position.

The dashed broken lines showing a head in the figures depict environmental subject matter that form no part of the claimed design. The long dashed broken lines represent disclaimed stitching. Additional short dashed broken lines depict portions of the bed sheet which form no part of the claimed design.

1 Claim, 18 Drawing Sheets
